US0D1066841S

(12) **United States Design Patent** (10) Patent No.: **US D1,066,841 S**
(45) Date of Patent: ** Mar. 11, 2025

(54) **VACUUM CLEANER BODY**

(71) Applicant: **LG ELECTRONICS INC.**, Seoul (KR)

(72) Inventors: **Jaeyoung Kim**, Seoul (KR); **Hoil Jeon**, Seoul (KR); **Seongmin Kim**, Seoul (KR); **Donghwan Lee**, Seoul (KR); **Nerry Son**, Seoul (KR)

(73) Assignee: **LG ELECTRONICS INC.**, Seoul (KR)

(**) Term: **15 Years**

(21) Appl. No.: **35/518,595**

(22) Filed: **Oct. 11, 2022**

(80) **Hague Agreement Data**

Int. Filing Date: **Oct. 11, 2022**

Int. Reg. No.: **DM/224405**

Int. Reg. Date: **Oct. 11, 2022**

Int. Reg. Pub. Date: **Oct. 13, 2023**

(30) **Foreign Application Priority Data**

Jun. 16, 2022 (KR) 30-2022-0024004

(51) **LOC (15) Cl.** **15-05**

(52) **U.S. Cl.**

USPC **D32/31**

(58) **Field of Classification Search**

USPC D15/199; D21/526, 578; D32/15, 16, D32/17, 18, 21, 23, 25, 31, 32, 38, 39

(57) **CLAIM**

The ornamental design for a vacuum cleaner body, as shown and described.

DESCRIPTION

1. Vacuum cleaner body

1.1 : Front perspective view

1.2 : Bottom perspective view

1.3 : Front

1.4 : Back

1.5 : Left

1.6 : Right

1.7 : Top

1.8 : Bottom

This article is used for cleaning floors, carpets, etc. by suction; the broken lines depict portions of the vacuum cleaner body that form no part of the claimed design; the shading lines are used to show the surface of the claimed design and do not represent its surface ornamentation.

1 Claim, 8 Drawing Sheets
